(57) **CLAIM**

The ornamental design for a pawl of a hand tool, as shown and described.

DESCRIPTION

FIG. 1 is a perspective view of the pawl of a hand tool showing my new design;

FIG. 2 is another perspective view of the pawl of a hand tool shown in FIG. 1;

FIG. 3 is a front view thereof; and,

FIG. 4 is a left view thereof.

The broken lines in the figures show portions of the pawl of a hand tool that form no part of the claimed design.
